UNITED STATES PATENT OFFICE.

THOMAS J. THORP, OF CHICAGO, ILLINOIS, ASSIGNOR OF ONE-HALF TO
GEORGE P. GOODALE, OF DETROIT, MICHIGAN.

METAL POST.

SPECIFICATION forming part of Letters Patent No. 438,121, dated October 7, 1890.

Application filed May 7, 1890. Serial No. 350,887. (No model.)

To all whom it may concern:

Be it known that I, THOMAS J. THORP, a citizen of the United States, residing at Chicago, in the county of Cook and State of Illinois, have invented certain new and useful Improvements in Metal Posts; and I do hereby declare the following to be a full, clear, and exact description of the invention, such as will enable others skilled in the art to which it appertains to make and use the same.

The object of the invention is to provide a metallic post suitable for use as telegraph-poles and other purposes; and it consists in the constructions hereinafter described, and particularly pointed out in the claims.

In the accompanying drawings, Figure 1 is a side elevation of the post, the ends being represented as broken away. Fig. 2 is a rear elevation of the upper part of the post. Fig. 3 is a plan of a wire-attaching plug or core and hook. Fig. 4 is a like view of a modified form. Fig. 5 is a longitudinal section of a coupling-ring. Fig. 6 is a similar view of a removable cap. Fig. 7 is an end view of a tube-section. Fig. 8 is a side elevation of a section of a modified means of supporting a post. Fig. 9 is a longitudinal section of the upper half of a cap-shaped plug, indicated near the top of Fig. 1, on a reduced scale; and Fig. 10 is a similar view of the lower half of a wire-securing plug, the wire-securing hooks being cut away.

The bottom section of the post herein shown and described, consisting of the tube with longitudinal opening and provided with rings having each a re-entrant angle fitting the opening and the hooks to receive and hold the fence-wire, is made the subject of application, Serial No. 359,370, filed by me July 21, 1890, and such matters are not claimed herein.

Numerical 1 denotes an incomplete tube open upon one side thereof longitudinally and having preferably a gradually-decreasing diameter toward one end, which in use will be the upper end, or directed toward the upper end of the post. This tube is made of metal, and preferably of sheet-steel, galvanized or otherwise protected from rust.

22 denote rings of different sizes, adapted to slip over the top and down upon the body of

a section of the post. The location of the ring can be determined by its size, the open tube permitting some slight degree of compression, so that the exact location of any particular ring can be varied to some extent by compressing the tube more or less by driving the ring down thereon. It is fastened to the tube by a screw or other means.

The ring is cast or otherwise formed with a re-entrant angle 3 of about ninety degrees, 60 having angular depressions at 4 4, in which the edges of the tube are forced when the ring is driven down upon it.

55 are hooks, cast or otherwise secured in the angular portion 3 and shaped like hammer-claws, or substantially as indicated in the drawings, for the attachment of barbed or other fence wire. Such wire can be secured to these hooks by a half-hitch, and will thus be very securely held.

6 denotes the lower half of a plug, preferably made in skeleton form. It is provided with hooks 5 5, similar to the hooks on rings 2 2, and with a screw-stem 7, which may be cast solid with the plug.

70 8 is a ring, having in each end a seat 9, formed by the edge of the ring, and an interior web or diaphragm 10, provided with a screw-threaded opening adapted to permit the screw 7 to pass through the same.

75 11 is a cap-shaped plug, (shown on a comparatively small scale in Fig. 9,) which may have a skeleton form, and which is provided with a screw-threaded opening to receive the end of a screw-stem 7. These devices are 85 used for coupling tube-sections of the post. The plug 6 being placed in the lower tube-section near its top, the cap-shaped plug is screwed thereon, the upper end of the said tube-section finding a seat in the ring and 90 bearing against the web therein. The screw 7 extends through the web 10 of the ring 8, and upon its free end is screwed the plug 11 after it has been placed in the bottom of an upper tube-section, both sections being provided with the bent parts 16, and by these means the sections are firmly coupled. The 95 ends of the sections are notched, and the teeth 16 thus formed are bent inwardly at right angles to the wall of the tubes, and these teeth 100

are firmly clamped in the tube-seats within the ring 8 between the diaphragm 10 and plugs 6 and 11.

13 indicates an ornamental cap or finish 5 screwed upon the complete post, whether it consists of one or more sections.

14 is a heavy cap, that may be placed temporarily upon the lower post-section by screwing it thereon by the use of a plug like 6, provided with a suitable screw to engage a socket formed in the cap, and it is intended to receive the impact of the sledge blows when the post is driven in the ground, after which it is removed, and either the ornamental cap or another tube-section, as desired, is placed upon the section that has been driven into the earth.

15 indicates a modification of the wire-supporting hooks. They consist of arms, preferably extending upwardly from their point of attachment to the post, adapted to receive and hold a transverse wooden bar, upon which insulators may be arranged for supporting electric conductors.

Under many circumstances the tube driven into the ground will be sufficiently anchored; but when necessary or when special firmness and security are desired additional devices of any known character may be employed for giving greater stability. As many sections 25 may be coupled together as found convenient. In case posts higher than ordinary fence-posts are required it will be convenient to provide a section to be driven into the ground, and upon the top thereof can be coupled as many 30 sections as the circumstances of use require. It is not to be understood that the invention is limited to the uses named, as there are others that are contemplated by the invention—as, for example, it will be suitable for scaffolds 35 and like purposes, and in situations where the lower sections cannot be driven into the

ground it will be entirely practicable to secure the lower end thereof over and upon short posts attached to a horizontal frame or otherwise made stable, and other mechanical 45 changes can be made by those skilled in the art without departing from the invention.

Having thus described my invention, what I desire to secure by Letters Patent is—

1. The open tube-sections having their ends 50 serrated and the serrations or teeth bent at an angle to the tube-wall, combined with a plug having a screw-threaded stem, a ring having two seats for the tube ends therein and a screw-threaded axial opening, and also 55 with a similar section having a plug with screw-threaded opening, whereby the two plugs can be screwed together to clamp the tube-sections in the ring, substantially as set forth.

2. The tube-section having a serrated end and the serrations or teeth bent at an angle to the wall of the tube, a plug having a screw-stem, and a screw-threaded cap adapted to screw upon the plug-stem and clamp the teeth 65 or serrated portions between itself and the plug, whereby the end of the upper tube-section is kept in proper form and adapted to receive a finial 13, substantially as set forth.

3. The open tubular post provided with a 70 ring having a re-entrant angular part fitting the opening in the post, an angular bracket fitting and bolted to said angular part, and a bar provided with insulators fastened to said bracket, substantially as set forth.

In testimony whereof I affix my signature in presence of two witnesses.

THOMAS J. THORP.
